FIG. 3.

FIG. 4.

INVENTOR:
D. W. QUILLING
BY Whiteley and Ruckman
ATTORNEYS.

UNITED STATES PATENT OFFICE.

DELVAN W. QUILLING, OF MINNEAPOLIS, MINNESOTA.

DENTAL DEVICE.

Application filed March 16, 1922. Serial No. 544,075.

To all whom it may concern:

Be it known that I, DELVAN W. QUILLING, a citizen of the United States, residing at Minneapolis, in the county of Hennepin and 5 State of Minnesota, have invented certain new and useful Improvements in Dental Devices, of which the following is a specification.

My invention relates to dental devices, 10 and an object is to provide an instrument which will enable the dentist to remove wax inlay models and mount the same ready for investment without the help of an assistant and with one hand free to hold the mirror or 15 the cheeks and tongue of the patient. I accomplish the objects of my invention by providing forceps having cooperating grooves in the tips thereof for holding a sprue. There are preferably two sets of 20 these grooves, one set being at a right angle to the length of the forceps, and the other set being at an obtuse angle. The sprue which is held in one or the other of these sets of grooves is thereby positioned so that 25 it can readily reach any surface of any tooth. A tube for delivering a cooling jet is so positioned that the cooling medium will be directed upon the sprue for chilling the same. The nozzle of the tube carrying 30 the cooling medium is preferably so positioned that the thickest part of the sprue which is, of course, the part carrying the most heat, is chilled first, thereby eliminating flaking at the place where the inlay 35 model is engaged by the sprue.

The full objects and advantages of my invention will appear in connection with the detailed description, and the novel features embodied in my inventive idea will be 40 particularly pointed out in the claims.

In the accompanying drawings, Fig. 1 is a side elevational view of the device. Fig. 2 is a similar view with portions broken away and showing the manner in which a 45 sprue is used. Fig. 3 is a top plan view. Fig. 4 is a fragmentary view corresponding to Fig. 2 but showing the sprue held at a different angle.

Referring to the construction shown in 50 the drawings, the numerals 10 and 12 designate the two members of forceps which are connected to each other at the ends 14 adjacent springlike portions 16 and 18 as shown in Fig. 3. A pin 20 secured to one of the 55 members is received in a hole in the other member in order that the two members may

be kept properly positioned relatively to each other. The tips of the forceps are provided with two sets of grooves 22 and 24, the first set being right angularly disposed and 60 the other set being disposed at an obtuse angle, whereby a sprue 26 may be held either in the position shown in Fig. 2 or in the position shown in Fig. 4. A syringe is associated with the forceps preferably in the 65 following manner. A tube 28 is soldered along one of the members, as the member 12, and this tube has a nozzle 30 positioned so as to deliver cooling medium such as water directly to the sprue 26 when the latter 70 after having been heated is pushed into a wax model W which is in the cavity of a tooth T. The other end of the tube 28 is connected by a flexible tubing 32 with a bulb 34 for forcing out the water. 75

The operation and advantages of my invention will now be apparent. The instrument is held in one hand and after the pointed end of the sprue has been pushed into the wax model contained in the tooth cavity, 80 water is applied to the sprue with the bulb held in the same hand, thereby chilling the sprue and rigidly fixing it to the wax model. The instrument also holds the sprue in the correct position for heating as well as in 85 correct position for removal of the wax model from the tooth. The wax model can be removed from the tooth and carried to the base for investment without changing the grip on the forceps or removal of the 90 hand from the forceps until the wax model is firmly set for investment. During the entire operation, one hand of the operator is left free for duties furthering the convenience of the operation. Should the operator desire to further burnish the wax 95 model, it can be left in the tooth cavity with the sprue attached. At the desired time, the forceps can again be applied to the sprue and by pressure on the bulb, the entire margins of the model can be chilled and the 100 model then removed. If further trial is desirable, the model can again be carried to the tooth cavity and the same procedure carried out. The advantages resulting from 105 the use of my appliance may be summarized as follows:

1. It eliminates the necessity of an assistant.
2. It holds the sprue for heating.
3. It carries this sprue to correct position.

4. It chills the sprue at the point of most heat first, thereby fixing the sprue to the model without flaking.
5. It permits removal of the model without changing the grip of the hand.
6. The model can be carried to the base for mounting without change of grip.
7. The model can be replaced in the cavity for further burnishing if desired.
10. 8. The model can then be completely chilled before removing by further pressure on the bulb.
9. It leaves one hand free during the entire procedure for holding either the tongue or cheeks or a mouth mirror.
15. 10. It eliminates danger of fracturing the margins of the wax model.

I claim:

1. A dental appliance comprising a holder having provision for holding a sprue at different angles, and means carried by said holder for directing a cooling jet upon said sprue.
2. A dental appliance comprising a holder for holding a sprue, and means carried by said holder in such position as to direct a cooling jet upon the thickest portion of said sprue.
3. A dental appliance comprising forceps

for holding a sprue, and means carried by said forceps for directing a cooling jet upon said sprue.

4. A dental appliance comprising forceps for holding a sprue and a tube carried by said forceps, said tube having a nozzle for directing a cooling jet upon said sprue.

5. A dental appliance comprising forceps having grooves in the free ends thereof for holding a sprue, and a tube carried by said forceps, said tube having a nozzle for directing a cooling jet upon said sprue.

6. A dental appliance comprising forceps having sets of grooves disposed at different angles in the free ends thereof for holding a sprue at different inclinations, and a tube carried by said forceps, said tube having a nozzle for directing a cooling jet upon said sprue.

7. A dental appliance comprising forceps for holding a sprue, a tube secured to one of the members of said forceps, said tube having a nozzle for directing a cooling jet upon the sprue, and a bulb connected with said tube.

In testimony whereof I hereunto affix my signature.

DELVAN W. QUILLING.
